United States Patent Office

Des. 180,525
Patented June 25, 1957

180,525

GAME BOARD

Edward R. Orr, San Diego, Calif.

Application July 27, 1956, Serial No. 42,425

Term of patent 7 years

(Cl. D34—5)

Fig. 1

The drawing is lined for green.

I claim:

The ornamental design for a game board, as shown and described.
